DESIGN FOR A SWEATER

Leon Singer, New York, N. Y., assignor to Supreme Knitwear Company, St. Louis, Mo., a corporation of Missouri

Application September 19, 1946, Serial No. 133,408

Term of patent 14 years

(Cl. D3—4)

To all whom it may concern:

Be it known that I, Leon Singer, a citizen of the United States, residing at the city of New York, county of New York, State of New York, have invented a new, original, and ornamental Design for a Sweater, of which the following is a specification, reference being made to the accompanying drawing, forming a part thereof.

The figure on the drawing is a front elevational view of a sweater, showing my new design.

The back of the sweater is plain and unornamented.

I claim:

The ornamental design for a sweater, substantially as shown and described.

LEON SINGER.
